G. H. PETERS AND R. E. SHOARS.

ASH SIFTER.

APPLICATION FILED NOV. 18, 1918.

1,391,073.

Patented Sept. 20, 1921.

UNITED STATES PATENT OFFICE.

GUSTAV H. PETERS AND RAYMOND E. SHOARS, OF MILWAUKEE, WISCONSIN.

ASH-SIFTER.

1,391,073.

Specification of Letters Patent. Patented Sept. 20, 1921.

Application filed November 18, 1918. Serial No. 263,006.

To all whom it may concern:

Be it known that we, GUSTAV H. PETERS, a subject of Germany, and RAYMOND E. SHOARS, a citizen of the United States, and residents of Milwaukee, in the county of Milwaukee and State of Wisconsin, have invented new and useful Improvements in Ash-Sifters, of which the following is a description, reference being had to the accompanying drawings which are a part of this specification.

The invention relates to ash sifters and is fully described and explained in the following specification and shown in the accompanying drawings in which:

Figure 1 is a vertical sectional view through the device embodying the invention taken on the line 1—1 of Fig. 2.

Fig. 2 is a plan view, parts being broken away and parts being shown in section;

Fig. 3 is a section taken on the line 3—3 of Fig. 1.

In the drawings, the numeral 4 designates a feeding hopper having inclined walls 5 and a bottom opening 6 which is in communication with an inclined chute 7 having side walls 8, top wall 9 and an open bottom for a greater portion of its length covered by a screen 10 removably mounted on inturned flanges 8' on the side walls 8, the end of the chute terminating in an enlarged spout or discharge opening 11.

The bottom opening 6 is normally closed by means of a flat plate valve 12 hingedly connected at one side to one of the inclined walls 5 and normally held in closing position by means of an arm 13 carrying a weight 14 at its outer end.

Hingedly secured to each side wall 8 of the chute 7 by a hinge plate 15' is a side plate 15 and one end of each plate is removably secured to an inclined end wall 16 by means of a bolt 17. An end plate 18 is hingedly secured to the upper end wall 19 of the chute 7 and has flanged sides 18' removably secured to the side plates 15 by bolts 20. The plates 15 and 18 and end wall 16 form a delivery hopper 21.

The plate 18 is provided with an outwardly extending flange 22 and the end wall 16 with a similar flange 23 so that an ash receptacle 24 having guideways 25 formed in its ends slidably engaging the flanges 22 and 23 may be removably connected to and disposed beneath the hopper 21.

The side edges at the bottom of the spout

11 are provided with flanges 27 similar to the flanges 22 and 23 so that a coal receptacle 28 having flanged guideways 29, similar to the guideways 25, may slidably engage the flanges 27 to removably connect the receptacle 28 to the end of the spout 11. The device is held off the floor or other support so that the coal and ash receptacles may be readily removed by means of legs 30 and 31. The legs 30 are pivotally secured at their upper ends to the end walls of the hopper 4 by bolts 30' so that they may be folded up against the side of the chute 7 when not in use and when in use they are held in upright position by means of hooked lugs 32 secured to the end plate 18 and engageable with locking bolts 33 which are mounted in slots 34 in the legs 30. The legs 31 are pivotally secured to the side walls 8 by bolts 35 so that they may be folded up against the side of the chute when not in use and when in use they are held in upright position by means of hooked lugs 36 secured to said walls 8 and engageable with locking bolts 37 which are mounted in slots 38 in the legs 31.

With the construction above described the material to be sifted is dumped into the feeding hopper 4 and passes down through the opening 6 and due to its weight opens the valve 12. It then rolls or slides along the screened bottom of the chute 7 and the finer particles such as ashes fall through the screen 10 into the hopper 21 and receptacle 24 while the larger particles such as the unburnt coal pass down the chute 7 through the spout 11 and into the receptacle 28.

The plate valve 12 and tight joints between the various parts of the device prevent the escape of dust from the device.

Owing to the fact that the receptacles 24 and 28 are removably secured to the device and that the side plates 15, end plate 18 and legs 30 and 31 are provided with hinged joints, the device may be folded up into compact form for shipping or storing.

What we claim as our invention is:

1. A closed ash sifter, comprising an inclined casing having foldable side and end walls and an open bottom portion, end portions of the casing also being open, an inclined screen mounted in the casing, a gated hopper connected to the casing wall forming one of the end openings, a cinder receptacle 105 removably connected to the casing wall forming the other end opening, an ash receptacle 110

removably connected to the casing and closing the bottom opening, and foldable legs for supporting the casing and the receptacles.

2. A closed ash sifter, comprising an inclined casing having foldable side and end walls and an open bottom portion, end portions of the casing also being open, a hopper mounted on the upper open end of the casing and having a gate for normally closing the adjacent casing end opening, a cinder receptacle removably connected to the

lower end of the casing and closing the lower end opening, an ash receptacle removably connected to the casing and closing the bottom opening, supporting legs pivotally connected to the opposite sides of the casing, and means for locking the legs in supporting position.

In testimony whereof, we affix our signatures.

GUSTAV H. PETERS.
RAYMOND E. SHOARS.
